BURNER

Eugen Ryschkewitsch, Frankfort-on-the-Main,
GermanyApplication February 9, 1931, Serial No. 514,596
In Germany February 15, 1930

14 Claims. (Cl. 158—99)

An industrial burner of a novel construction forms the subject of this invention, by means of which the attainment of particularly high temperatures even during the utilization of inferior fuels is made possible as well as a correct control of the temperature and on the other hand a particularly economical operation with low fuel consumption.

The essential idea of the invention is that in 10 the inner space of the burner (e. g. a gas burner or the like), in which the combustion of a combustible gas mixed with air or oxygen takes place, the surface which accelerates catalytically the combustion process is enlarged by the arrangement of projections (e. g. by ribs running along the walls or by special built-in portions) which are arranged to run in the direction of flow of fuel stream, so that the speed of travel through the burner of the gaseous mixture is only immaterially diminished.

The favourable influence on the combustion process arises in a particularly high measure from the fact that the enlarged surface in the burner is formed of, or is covered with, materials which produce a strong emission of electrons at high temperatures. For this, the oxides of the alkaline earths and other high temperature-withstanding oxides, as magnesium oxide, zirconium oxide, thorium oxide and others, having proved 30 suitable.

It has been proved that for any predetermined amount of a chosen fuel to be burnt in a unit of time a certain minimum size of contact surface in the combustion space is requisite. This depends on the temperature in the combustion space and the nature of the materials of construction.

As an example it may be given: that taking illuminating gas and a temperature of about 40 1800°-2000° C., for the contact combustion of 1 cubic meter of the gas per hour a total surface in the combustion space of at least 200 square centimeters is required if the constructional material is magnesia. The gas and air mixture 45 should be brought into as complete a contact as possible with the contact surface.

It should be recognized from this that the narrowest possible capillary intermediate space hitherto always employed is not required, but one 50 should provide comparatively wide passages and intermediate spaces which should be all the wider as the length of the combustion zone increases. By way of example: it is suitable for a length of combustion space of about 80 mm. to select about 55 5 to 6 mm. for an average distance between oppo-

sitely lying contact surfaces; for a length of 800 mm., an average distance of about 40 mm., and so on.

The size of the combustion space should be determined so that the time during which the 5 fuel gases are in the combustion space is about 1/50 to 1/200 second when the furnace is at about 2000° C.

For the practical embodiment, then, certain 10 limits for the ratio of the contact surface to the combustion space result from a consideration of these points, and indeed it has been demonstrated that for one litre of combustion space not less than about 15 square decimeters, preferably about 20 dm², of contact surface, should be employed. 15 These instructions hold good both when operating the burner with a gaseous fuel and in the case of use of finely divided liquid fuels or pulverized fuels.

The contact surface accelerates the rapidity of 20 the combustion reaction so much that the chemical change takes place completely in the time specified. Comparatively large intermediate spaces between suitably disposed contact surfaces, 25 which in general should run in the direction of the gas stream, allow very low pressures to be used on the reacting gases for driving the latter through the combustion space. It is sufficient to have the usual gas pressure of about 20-40 mm. of water and the comparatively very low 30 pressure of a centrifugal fan, as low as 100 mm. water, in order to operate the herein-described burner. By this means temperatures can be obtained which lie far above those otherwise obtainable in like circumstances. 35

In the accompanying drawing different constructional forms of the invention are given by way of example.

Fig. 1 shows a burner in accordance with the 40 invention in longitudinal section,

Fig. 2 shows a burner as in Fig. 1 but in plan view with the central inset body omitted,

Figures 3 and 4 are similar views of a further constructional form thereof.

In Figure 1 the reference numeral 1 represents a housing, made for example of cast iron, on which a gas inlet connection 2 is arranged. The connection 2 of the gas inlet is provided with nozzles 3 which are in communication with the atmosphere so that the inflowing gases draw in 50 a suitable amount of air. The internal construction of the burner housing consists essentially of a refractory lining sleeve 4 and a mantle or burner body proper 5 which can be suitably constructed of a number of separate parts 7 as- 55

sembled together so as to project rib-like into the interior of the burner. The joints between the parts 7 will be made tight in any suitable manner. If necessary the ribs 7 can even be set in a special refractory sleeve piece which has approximately the form of a truncated cone. Further, a suitable, conically formed, inset body 8 can be arranged in the upper portion of the burner mouth it being supported in any suitable manner, e. g., as indicated at 8'. Between the walls 4 and 5 is a circular passage 9 which is in communication through openings 10 with the atmosphere, or with a supply of compressed air under suitable pressure e. g. as low as 100 mm. water pressure, and through openings 11 with the combustion space. In Fig. 2 the fire proof inset body 8 is omitted, so that the interior of the burner is not covered in the illustration.

In such a gas burner, the gaseous fuel streaming into the burner through the gas connection 2 draws in a certain amount of air and with the air entering at 11 burns completely in the combustion space lying between the ribs 7 and the inset body 8. On account of the relatively low thickness which the gas layer filling the combustion space has at every point between the ribs 7, or between these and the inset body 8, every particle is subject to the intensive action of the electron-emitting surface of the burner so that on a comparatively short passage a complete combustion even of low value gases with extraordinary high temperature increase can be obtained. The effect is enhanced owing to the air entering at 9 being intensively preheated in the circular space between the burner body 5 and the outer wall 4. Similarly the effect can be increased by high preheating of the combustible gases, e. g. to 500° C. and higher.

In Figures 3 and 4 a further constructional form is illustrated in which the internal components 17 are annular and are supported from each other by radial ribs or distance pieces 18.

Burners of the described kind can be employed advantageously wherever a high initial temperature with rapid combustion and complete utilization of the fuel is desired, as for example with boiler furnaces, with metal melting furnaces, and in numerous other instances. Particular advantages flow also in the combustion of inferior fuel such as in the combustion of poor furnace gases, as even in such cases an extraordinary high temperature can be obtained with the new burner constructions.

It may appear surprising that even with pulverized fuels such an effect is attainable; it is explained however in that, because of the high temperature in the burner chamber, the combustion of the carbonaceous materials to carbon monoxide takes place exceptionally rapidly and completely, without wall catalysis; and the further oxidation of the so formed carbon-monoxide proceeds on the wall surface in the manner described with extreme acceleration.

I claim:

1. A burner having a combustion chamber provided with a mantle divided into a plurality of annular sections, the interior of said mantle having inserted therein a plurality of bodies made of catalytically acting material highly resistant to fire, the inserted bodies dividing the interior of the combustion chamber into a plurality of canals whose length is at least equal to the diameter of the chamber and providing a construction, which offers little resistance to the flow of the gaseous mixture and whereby the area of the

catalytic contact surface of the combustion chamber is at least 15 square decimeters to one liter of combustion chamber volume.

2. A burner having a combustion chamber provided with a mantle divided into a plurality of 5 annular sections, the interior of said mantle having inserted therein a plurality of bodies made of catalytically acting material highly resistant to fire, the inserted bodies dividing the interior of the combustion chamber into a plurality of 10 canals whose length is at least equal to the width of the combustion chamber and is great relative to their transverse dimensions and providing a construction which offers little resistance to the flow of the gaseous mixture and whereby the area 15 of the catalytic contact surface of the combustion chamber is at least 15 square decimeters to one liter of combustion chamber volume.

3. A burner having a combustion chamber, the interior of said burner being lined with a plurality of annular sections of fire resistant material, a plurality of insert bodies of catalytic material which is highly resistant to fire located within said sections and dividing the combustion chamber into a plurality of straight channels 25 whose length is at least equal to the diameter of said chamber, whereby little resistance is offered to the flow of the gas mixture and wherein in the area of the catalytic contact surfaces is at least four hundred square decimeters for a 30 consumption of one kilogram of combustible material per hour.

4. A burner having a catalytic combustion chamber, said chamber having a lining composed of a plurality of readily interchangeable annular 35 sections, said annular sections carrying independent annular bodies of catalytic material highly resistant to fire and dividing the combustion chamber into a plurality of concentric passages which are at least equal in length to the diameter 40 of the chamber, said inserted bodies offering little resistance to the flow of fuel.

5. A construction as defined in claim 1 in which the inserted bodies are interchangeable and consist of materials of high electron emitting powers. 45

6. A construction as defined in claim 1 in which the inserted bodies are interchangeable and are composed of metallic earth oxides.

7. A burner having a combustion chamber, said burner having a mantle composed of a plurality 50 of annular sections in the interior of which are inserted a plurality of bodies of catalytic material which is highly resistant to fire, said bodies dividing the combustion chamber into a plurality of straight channels and providing a comparatively 55 large combustion contact surface, the said channels having a great length relative to the transverse dimension of the chamber and offering little resistance to the flow of the gas mixture, the width of the catalytically acting combustion channels varying from 5 mm. to about 40 mm., where the length of the combustion chamber varies from 80 mm. to about 800 mm.

8. A burner having a combustion chamber provided with a mantle, the interior of the said mantle having inserted therein a plurality of bodies made of catalytically acting material highly resistant to fire, the inserted bodies dividing the interior of the combustion chamber into a plurality of canals whose length is great relative to 70 the transverse dimension of the chamber and providing a construction, which offers little resistance to the flow of the gaseous mixture and whereby the area of the catalytic contact surface of the combustion chamber is at least 15 square 75

decimeters to one liter of combustion chamber volume.

9. A burner for fluent fuel said burner having a combustion chamber provided with a refractory mantle and elongated relatively thin bodies of fire resistant material of high electron emitting power alined with the direction of fuel flow, said bodies dividing the combustion chamber into relatively straight long narrow unobstructed channels extending in the direction of flow of the fuel, said channels having relatively large catalytic wall surface as compared with the cubical contents of the chamber, substantially as set forth.

10. A device as in claim 9, the catalytic surface being at least 15 square decimeters to 1 liter of space in said chamber.

11. A device as in claim 9, the width of the channel being about 1/15 to 1/20 of the length of the combustion chamber.

12. A device as in claim 9, said refractory man-

tle being divided into annular sections each carrying independent sets of catalytic bodies.

13. A device as in claim 9, the catalytic surface being at least 15 square decimeters to 1 liter of space in said chamber, the width of the channels being about 1/15 to 1/20 of the length of said chamber, and the refractory mantle being divided into annular sections each carrying independent sets of catalytic bodies.

14. A burner for fluent fuels having a combustion chamber, a mantle in said chamber having supporting internal members of fire-resistant material acting catalytically on such fuels, said members being of relatively great length in proportion to their thickness and extending lengthwise of the combustion chamber, so as to provide long, straight narrow unobstructed channels with a large catalytic wall surface, substantially as set forth.
